UNITED STATES PATENT OFFICE.

FRANK P. BOATMAN, OF INDIANAPOLIS, INDIANA, ASSIGNOR TO THE
MORRIS BOX LID COMPANY, OF PITTSBURG, PENNSYLVANIA.

CAR-AXLE-BOX LID.

SPECIFICATION forming part of Letters Patent No. 483,801, dated October 4, 1892.

Application filed May 21, 1892. Serial No. 433,867. (No model.)

To all whom it may concern:

Be it known that I, FRANK P. BOATMAN, a citizen of the United States, residing at Indianapolis, in the county of Marion and State of Indiana, have invented certain new and useful 5 Improvements in Car-Axle-Box Lids; and I do hereby declare the following to be a full, clear, and exact description of the invention, such as will enable others skilled in the art to which 10 it appertains to make and use the same, reference being had to the accompanying drawings, and to the figures of reference marked thereon, which form a part of this specification.

15 The sheet-metal lid or cover for car-axle boxes now in use is arranged on a seat inclining downward from the top of the box and is pivoted at one side of the box, so as to be swung or turned edgewise with a sliding 20 movement upward to uncover the box-opening, and when closed rests upon a rib or shoulder at the lower side of said opening.

As the lid, which I prefer to make of steel, 25 is comparatively thin and is subject to more or less vibration under the motion of the cars against this box rib or shoulder on which it rests, and as the lid is often opened for the supply of oil to the journal of the axle and closed with more or less force against said box- 30 shoulder, it is from these causes that the lid is caused to cut into this box-shoulder and thereby allowed to assume a position oblique to the opening and consequently uncover its upper corner and expose the oil-chamber to 35 dust and cinders, which would pass through the crack along the upper edge of the lid into the box, and in time the box-shoulder would be cut off. My improvement provides a remedy for this cutting action of the steel lid into 40 the box by forming the lower edge of the lid with a turned-up lip or flange, so as to form thereby a comparatively-broad surface bearing the full length of the lid, by which the latter is supported upon the box-shoulder, 45 and thereby prevent any cutting action on the latter and maintain the lid in true position upon its seat.

The accompanying drawings show in Figure 1 the position the steel lid will take in 50 cutting into its supporting-shoulder at the

lower edge of the box-opening. Fig. 2 shows the steel flanged lid in cross-section in its relation to the box-seat and to its supporting-shoulder; and Fig. 3 is a perspective view of the lid, one edge of which is formed with the 55 turned-up flange-bearing; and Fig. 4 shows the lid as having partly cut off the shoulder of the box.

The opening in the axle-box is made with an inclined seat 1, standing downward from 60 the top, and has ribs or shoulders 2 at its lower and upper edges, between which the lid 3 is adapted to fit and be seated to close the opening.

I prefer to make the lid of sheet-steel, and 65 it is pivotally connected at one end to a side projection 4 of the box, so as to be opened and closed by an edgewise-swinging movement over the opening. Its pivot connection may be of any suitable construction that will 70 give to the lid a spring function constantly exerted to press and maintain the lid upon its seat and that will permit it to be raised from its seat and swung or slid open upward over and upon the shoulder at the upper edge 75 of the box-opening.

At its lower edge the lid is upset to form a flange or rib 5, of a length equal to that of the lid, so as to form a surface bearing upon the lower box-shoulder. I make this bearing- 80 flange at right angles to the lid, so as to form a close joint with the shoulder, and of a height preferably equal to that of the shoulder, so that the lid-flange rests against the latter with a walled surface instead of a cutting-edge. This edge flange, moreover, increases the rigidity of the lid and keeps it in 85 a flat condition for close seating.

As before stated, the pivoting and spring function of the lid may be provided in different ways; but I prefer the construction shown, in which the pivoted end of the lid is formed with a spring-tongue 6, bent or doubled, so that it overlaps the lid a distance sufficient to cause it to form a pivoted part having the 90 function of a spring standing toward the free end of the lid and exerting its force directly upon the lid to hold it firmly in its closed position and to hold it in position when opened. The pivoted end of the lid is reduced in 95 100

width and is bent outward to form the spring-tongue, the lapped parts being formed with registering perforations 7 and 8, through which the pivot-bolt 9 passes into the box projection and is secured by a nut, so that the bolt-head bearing on the outside of the spring-tongue allows the latter to be compressed to give it more or less tension on the lid. The spring-tongue will be suitably tempered and rigid enough to hold the lid upon its seat and allow it to be raised at its free end to open it and to hold it when open upon the upper shoulder while supplying oil to the journal. The spring part stands longitudinally in central line with the lid, and I prefer to make it with a swell 11 at the bend, and the spring-pressure exerted upon the lid by the spring part can be adjusted by turning the nut of the bolt. The lid is formed with a suitable handle part, by which it may be opened and closed, and the lid may be formed with a central raised and corrugated part 12 to stiffen it, so that although made thin and light its middle and edge upset parts gives it sufficient stiffness to prevent bending, and that it can only yield at its pivot.

It is important to notice that the lid having the bearing-flange at its lower edge rests upon the box-shoulder throughout its length, so that there is no strain whatever upon the pivot-bolt, and while I prefer to form the seat for the lid on a downward incline at the upper side of the box I do not wish to be confined to this particular construction, so long

as the lid is formed with the outward-stand- 35
ing bearing-flange at its lower edge.

I claim as my improvement—

1. The combination, with a car-axle box having its lid-seat standing on a downward incline and formed with a rib or shoulder at 40 the lower side of its opening, of a lid pivoted at the side of the box, formed with a lip or flange standing upward at its lower edge, whereby to form a long surface bearing upon the inner side of said box-shoulder, for the 45 purpose stated.

2. A car-axle-box lid or cover formed with an outward-upset lip or flange on its lower edge to form a long surface bearing on the box at the lower edge of its opening and provision at one end for a pivotal connection, substantially as described.

3. A car-axle-box lid or cover formed with a lapping spring-tongue at one end having registering holes in the lapped parts and an 55 outwardly-upset flange or lip at its lower edge, for the purpose stated.

4. A car-axle-box lid having a pivot-attaching end having a spring function and an outward-upset bearing lip or flange along its 65 lower edge, for the purpose stated.

In testimony whereof I affix my signature in presence of two witnesses.

FRANK P. BOATMAN.
